DIEING-OUT MACHINE

Basil A. Strout, Farmingdale, Maine, assignor to
 United Shoe Machinery Corporation, Flemington, N. J., a corporation of New Jersey

Application September 8, 1945, Serial No. 615,198

8 Claims. (Cl. 164—23)

1

This invention relates to dieing-out machines of the type in which freely movable dies are forced through sheet material to form blanks, and more particularly to mechanism for automatically counting cut blanks as they are formed.

In connection with the operation of die presses, such as clicking machines commonly used in the trade to produce shoe part blanks by means of dies, a considerable part of the time of the operator is consumed in counting the blanks produced. This is due to the fact that an operator, who may produce several hundreds or thousands of blanks each day, is likely to operate upon several different orders requiring various changes in the dies used, with a varying number of blanks required for each die. Since the dies are of different sizes and types, the operator must exercise considerable care in counting the pieces as he cuts them, and, in order to be economical of material, he should not produce more than the required number of any particular size, style, or type of blank. It is an object of the present invention to provide, in a machine of the type referred to, mechanism for automatically counting and registering the number of blanks of various kinds produced, thereby relieving the operator from counting blanks.

To this end and as illustrated, the machine is provided with a plurality of electrically operated registering devices, any one of which, selectively, may be placed in circuit with operating mechanism for initiating an operation to produce a blank. Thus, when a cutting operation takes place, the action which initiates it also initiates an operation of one or another of the registering devices, with the result that a record of the blank cut is made. Preferably and as shown, this is accomplished by mounting a starting handle for initiating operation of a clutch, which in turn causes the descent of a presser arm upon a die, so that the handle may also initiate, selectively, the operation of any one of the registering devices. Preferably, each registering device is associated with a particular type or size of die, so that, when the operator makes use of a particular die, he operates the starting handle in such a way as to produce a recording of the cut upon the registering device corresponding to the particular die which he is using.

Another feature of the invention consists in mechanism for preventing operation of any one of the registering devices until after the arm has been moved away from the position in which it made its previous cut. In this way, the recording of two strokes of the arm for a single cut is

2

avoided, thus tending to improve the accuracy of the count. Preferably and as illustrated, this mechanism comprises a trip switch in circuit with the registering devices, and mounted at the top of the post of the machine. The switch comprises two contacts, one of which is carried by a pivoted lever normally held away from the contact at the upper end of the spindle by a latch plate. The plate is carried by a lifting lever mounted for universal movement upon the frame of the machine and having a dog which engages a ratchet carried by the spindle in such manner that when the arm is moved away from the position of its previous cut, the latch plate will be disengaged permitting the trip switch to be closed and thus conditioning the circuit for an operation of the starting handle.

These and other features of the invention are disclosed in the following specification and in the accompanying drawings, and are pointed out in the claims.

In the drawings,

Fig. 1 is a perspective view of a clicking machine embodying the registering mechanism of my invention;

Fig. 2 is a front elevation of a portion of the machine illustrating the mounting of the registering devices;

Fig. 3 is a view in side elevation of the manually operable starting lever and registering device control;

Fig. 4 is a plan view, partly in section, of the lower portion of the mechanism shown in Fig. 3;

Fig. 5 is a vertical cross sectional view through the mechanism shown in Fig. 3;

Fig. 6 is a vertical cross sectional view of the starting handle shown in operative relation to one of the registering device circuit controlling switches;

Fig. 7 is a vertical cross section through the lower portion of the starting handle;

Fig. 8 is a perspective view of the upper portion of the clicking machine showing the mechanism for controlling the trip switch;

Fig. 9 is a plan view of the trip switch and control mechanism;

Fig. 10 is a view in side elevation, partly in section, of the mechanism shown in Fig. 9;

Fig. 11 is an end elevation of the lifting lever and pawl and associated mechanism; and

Fig. 12 is a wiring diagram of the registering device and trip switch control circuits.

The invention is embodied in a clicking machine of the type disclosed in United States Letters Patent No. 921,503, granted May 11, 1909,

upon application of Arthur Bates, to which reference may be had for details of clicking machine structure not herein illustrated. As shown in Fig. 1, the present machine comprises a frame 10 supporting a cutting block 12 and having a vertically reciprocable post 14 carrying a presser arm or beam 16, movable about the axis of the post across the surface of the cutting block and movable upon the reciprocation of the post toward and away from the cutting block in performing a pressure-applying operation upon a die positioned upon work upon the cutting block. The post is reciprocated by an eccentric 18 on a rotary shaft 20 arranged to be connected to a power driven flywheel 22 by a one-revolution clutch 24. Operation of the clutch is initiated by a starting lever 26 arranged to cause clutch engagement upon upward movement of a trip rod 28 adapted to be lifted by a solenoid 30 in response to operation of a starting handle 32 mounted upon the end of the arm 16.

In order that the operator may readily record operations of the presser member performed in producing each of several different kinds of blanks, there is provided a plurality of registering devices 34 and 35 for recording the number of blanks produced. Each of these is connected in series with the solenoid 30, a trip switch 36 at the upper end of the beam, and one of several registering device control switches 38 and 40 arranged to be closed selectively by operation of the starting handle 32. Thus, when the starting handle is operated to initiate an operation of the presser arm, each stroke of the arm is recorded upon one or another of the registering devices. There is also provided means for initiating operation of the presser arm independently of the registering devices. This means comprises a separate circuit which includes the solenoid and a control switch 42, Fig. 5, also arranged to be operated by the starting handle.

The starting handle 32 is carried upon a switch operating rod 44 pivotally mounted upon a casing 46 at the outer end of the presser arm 16. The casing, best shown in Figs. 3, 4, 5 and 6, has a lower hollow cylindrical portion 48, having a reduced depending portion 50 secured by means of a set screw 52 to an upstanding stud 54 on the presser arm.

The registering device control switches 38 and 40 are of the push-button type, and are commonly mounted in the casing so that their push buttons 56 extend radially of the casing. The control switch 42 is of a similar type, and is mounted in the depending portion 50 of the casing with its push button 58 extending upwardly.

In order to operate the switches 38 and 40, the switch operating rod 44 is provided at its lower end with two spaced sets of radial arms 60 and 62. Each set of arms comprises four members arranged in a star pattern, the upper set 62 being offset angularly about the rod 44 by 45° from the lower set 60, and the lower set being normally located in the plane of the push buttons 56. The rod 44 is mounted for movement under actuation of the starting handle 32, both heightwise and angularly out of vertical position, so that one or another of the arms can be moved to engage a selected push button. To provide suitable mounting for the rod 44, the upper portion of the casing comprises a cover plate 64 secured to the casing by screws 66. The central portion of the cover plate has an upwardly extending hollow boss 68 forming a sleeve surrounding the rod 44, and the upper end of the boss is provided with a concave

seat 70 adapted to receive a ball member 72 having a bore in which is positioned the starting handle rod 44. The rod has a longitudinally extending keyway 74, in which is located a key 76, Fig. 7, engaging the ball member, thus to provide for sliding movement of the rod relatively to the ball member, but preventing rotation of the rod. The ball member is retained in position on the seat 70 by a plate 78 resting on the top of the boss and bearing upon the upper portion of the ball member. The plate 78 is forced toward the boss by springs 80, located in bores 82 extending vertically of the boss and surrounding four studs 84, which extend through the plate and through the bores in the boss. The springs bear against the upper end walls of the bores and upon nuts 86 at the lower ends of the studs. This arrangement permits movement of the rod 44 angularly out of the vertical position, as shown in Fig. 6, but, when released, the rod will be returned to its vertical position by operation of the springs 80 and plate 78.

Preferably and as shown, the registering devices 34, 35 are of the solenoid operated type and, for convenience, are mounted upon a plate 88 extending in a vertical direction and positioned near the upper end of the frame of the machine, in such a way as to be readily visible to an operator standing in front of the cutting block. The registering devices are arranged in two sets upon the plate, in such a way that the positions of the registering devices correspond to the two series of radial arms 60, 62 upon the starting handle. Thus, it will be noted that the four arms of the upper series are arranged in the form of a diamond standing on one of its corners, whereas the projections of the lower set are arranged in the form of a rectangle resting on its side. In this way, by having the registering devices arranged on the supporting plate in the manner corresponding to the arrangement of the two series of arms, the operator, by glancing at the registering devices, can readily determine in which direction to move the starting handle in order to record the operation of the machine upon a particular registering device, which, of course, would correspond to the particular die being used at the time.

The starting handle 32, which is slidable upon the rod 44 is normally supported somewhat above the boss 68 by a spring 90 seated in a cavity 92 in the lower part of the handle and bearing upon a washer 94 resting upon the plate 78.

For operating the control switch 42 there is provided a plunger 96 slidably mounted within the rod 44 having at one end a button 98, which normally rests upon the upper surface of the handle 32. The lower end of the plunger bears a screw 100, the head of which is somewhat larger than the plunger 96 and is arranged to be received in a recess 101 in the lower end of the rod 44. Thus, in the position of the parts as shown in Fig. 5, the plunger is supported from the upper end of the handle 32 and the plunger screw 100, in turn, supports the rod 40. The upper end of the rod 44 terminates below the upper end of the handle, and, in the space between the rod and the button 98 is a collar 102, slidably relatively to the plunger and secured to the handle by a screw 104, there being a weak spring 106 surrounding the upper end of the plunger and bearing upon the upper end of the collar and the underside of the button 98. This construction is such that the handle 32, rod 44,

and plunger 96 are normally held in the position shown in Fig. 5, further upward movement of the rod being prevented by engagement of the key 76 with the lower end wall of the keyway 74, as best shown in Fig. 7. From this position, the rod 44 can be tilted in such manner as to cause one of the arms 60 to operate one of the switches 38, as shown in Fig. 6. When it is desired to operate one of the switches 40, the handle 32 is depressed against the pressure of the spring 90, with the result that the collar 102 engages the rod 44, forcing it downwardly until the upper set of arms 62 is disposed in the plane of the switches 38, 40, after which the rod can be tilted in a direction to operate a selected switch 40.

When the starting handle is close to the washer 94 with the collar 102 engaging the upper end of the rod, the spring 106 holds the button 98 of the plunger 96 some distance above the upper end of the handle 32, with the result that the plunger remains in its original position within the rod. However, when it is desired to operate the control switch 42, the button is depressed, thus projecting the plunger beyond the lower end of the rod a sufficient distance to cause the screw 100 to engage and operate the push button 58 of the switch 42.

To facilitate tilting movement of the rod in directions to operate a selected switch 38, there are provided four pins 108 depending from a plate 110, retained in a recess in the cover plate 64, and each positioned to enter between two adjacent arms 62, thus to guide an arm 60 toward its particular switch. Similarly, the arms 62, when the rod is in its lower position, are guided to a selected switch 40 by upstanding pins 112, each of which is positioned to enter between two of the adjacent arms 60 to guide an arm 62 toward its particular switch.

In the normal operation of the machine, a cutting die is placed upon material in position upon the block 12. The presser arm 16 is swung about the axis of the post 14 by means of the starting handle 32, until the arm is in position over the die. The starting handle is then moved in a direction to close one of the switches 38 or 40, corresponding to the registering device for recording the number of blanks cut by the particular die being used. If the trip switch 36 is closed, this initiates an operation of the presser arm to produce a blank, and also actuates one of the registering devices to record the cutting operation.

The purpose of the trip switch and its associated mechanism is to prevent repetition of the recording of the operation in producing a particular blank, in the event that the starting handle were to be operated a second time without swinging the arm from its position over the die. Accordingly, mechanism is provided for rendering the trip switch inoperative after a single registering operation until after the presser arm has been moved an appreciable distance away from its position in which the starting handle is tripped.

To this end, the trip switch 36 comprises a fixed contact 114, Figs. 1, 9, and 10, secured to the upper end of the post 14 by screws 115 and separated from the post by a plate of insulating material 116, and a movable contact 118 mounted on a plate of insulating material 119 secured to a lever arm 120 pivoted at 122 on an arm 124 of an upstanding bracket 126 secured to the upper end of the frame 10 of the machine. With the post in its uppermost position with the presser arm 75

raised above the block, the two trip switch contacts are held in engagement with each other by operation of a spring 128 connected to the lever 120 and to an upwardly extending stationary plate 130 supported upon the bracket 126.

In order to open the trip switch upon descent of the post, there is provided a latch arm 132, the upper end of which is secured to the lever arm 120 by a ball and socket connection 134. 10 The latch arm extends downwardly past the edge of a laterally extending plate 136 carried by the bracket, and has a notch 138 for engaging the edge of the plate, there being a spring 140 secured to the lower end of the latch arm and to the bracket for urging the latch arm toward the edge of the plate. Thus, when the post descends in producing a pressure-applying operation of the presser arm, the lever 120 rotates downwardly about its pivot 122, and the latch is engaged with the edge of the plate 136.

20 In order to condition the latch, the plate 136 is mounted upon a ball and socket connection 142 carried at the upper end of a stud 144 fixedly secured to the bracket. This connection permits movement of the plate heightwise of the bracket, and also movement angularly in a horizontal plane, the extent of movement angularly being limited by means of a leveling pin 146 secured to the ball and socket connection and extending into an elongated slot 148 in one side of the bracket.

25 Mounted upon the outer end of the plate 136 is a guideway 150, in which a pawl 152 is slideable toward or away from the teeth of a ratchet 154 secured to the post 14, the pawl normally being urged toward the ratchet teeth by a spring 156. Extending outwardly beyond the ratchet is a plate 158 operable upon upward movement of the post to engage the underside of the pawl 152 to 30 raise the pawl and the plate 136. The arm 120 carries a stop screw 160 arranged upon downward movement of the arm 120 to engage the upper surface of the plate 130, thus limiting downward movement of the lever 120.

35 The construction and arrangement of parts is such that, when the post moves downwardly, the plate 136, the latch 132, the lever 120 and the pawl 152 all move downwardly, the lever 120, however, being arrested in its downward movement by the plate 130. When the post moves upwardly, the plate 158 engages the pawl 152 and raises the plate 136, until the edge thereof is engaged by the latch. Further movement of the post upwardly results in carrying the plate as 40 well as the lever 120 upwardly, until the contact 118 is separated from the fixed contact 114, thus opening the trip switch. The switch will remain open until the post has been moved angularly a sufficient distance in a counterclockwise direction 45 (Fig. 9) to shift the plate 136 about its pivot by a sufficient distance to release the latch, whereupon the lever 120 drops and again closes the trip switch.

45 It is to be noted that the direction of the ratchet teeth is such that movement of the arm about the axis of the post in a clockwise direction will not effect closing of the trip switch. As a result of this, the presser arm must be moved a sufficient distance to clear the arm from its position over the die, either in a counterclockwise direction or in a clockwise direction, followed by return movement in a counterclockwise direction. In view of this, the trip switch will be open after each operation of the presser arm, which is 50 accompanied by an operation of the counting

device until the arm has been moved through a distance which is at least that required to uncover the particular die being used. Therefore, a second registering of the same blank or presser arm operation will not occur, even though the arm may be again brought down upon the blank through operation of the control switch 36, as sometimes might be necessary when operating upon heavy material which requires more than one stroke of the presser arm to produce a blank.

As shown in the wiring diagram, the clutch trip solenoid 30 is included in a power circuit, having main leads 162, connected to one side of the solenoid, and 164 connected to one side of the control switch 42. The other side of the control switch is connected to the solenoid by a lead 165. Since the switch 42 is in series with the solenoid, an operation of the presser arm can be accomplished independently of operation of the registering devices. Each of the switches 38 and 40 has a lead 166 extending from one side of the switch to the power line 164, and a lead 168 extending from the other side of the switch to one of the registering devices 34 or 35. From the other side of each of the registering devices there is a lead 170 extending to one side of the trip switch, there being a lead 172 from the other side of the trip switch to the solenoid. Thus, each of the registering devices 34, 35 can selectively be placed in circuit through a switch 38 or 40, the trip switch 36 and the solenoid 30. Consequently, when one of the switches 38, 40 is tripped a corresponding registering device will be operated, and at the same time the solenoid 30 will be operated to effect a pressure-applying operation of the presser arm.

In summarizing the operation of the machine, assuming that the trip switch 36 at the upper end of the post is closed, the operator positions a die upon sheet material on the block 12, grasps the starting handle 32 and swings the presser arm 16 into position over the die. He then tilts or depresses and tilts the handle 32, in order to close a selected switch 38 or 40 corresponding to one of the registering devices 34 or 35, which, in turn, the operator associates with the particular die being operated upon, with the result that the solenoid 30 initiates operation of the clutch 24 in effecting a pressure-applying operation of the arm 16 upon the die to produce a blank, and at the same time causes an operation of the selected registering device to record the production of the blank. As the post 14 descends during the pressure-applying operation, the trip switch 36 is opened and, when the post rises, the latch arm 132 engages the plate 136, and the plate is raised by engagement of the plate 158 with the pawl 152, thus also raising the lever 120 and opening the trip switch. If the operator finds it necessary to cause a second operation of the arm in producing the blank, he depresses the starting handle 32 as far as it will go, holding his thumb upon the button 98, with the result that the control switch 42 is actuated, causing a second operation of the presser arm without an attendant recording by a counting device. After the formation of the blank, the presser arm is swung away from the die and, in the manner above set forth, the ratchet 154 acting upon the pawl 152 effects a release of the latch 132, with the result that the lever 120 drops, again closing the trip switch 36, conditioning it for a subsequent operation.

Having described my invention, what I claim as new and desire to secure by Letters Patent of the United States is:

1. A clicking machine comprising a frame, a cutting block mounted in the frame, a post located at one side of the cutting block, a presser arm carried by the post, power-operated means for reciprocating the post, and means for initiating a power operation including a clutch, said machine having a solenoid for operating the clutch, means for initiating an operation of the solenoid comprising a starting handle mounted upon the presser arm, a switch mounted for operative relation by the starting handle, and an electric circuit extending through the solenoid and through the switch, a registering device, an electric circuit extending through the solenoid and the registering device, and a second switch mounted in operative relation to the arm, and means mounting the starting handle for movement to close either of the switches selectively, thereby to initiate a pressure-applying operation and a simultaneous operation of the registering device, or to initiate a pressure-applying operation independently of operation of the registering device.

2. A clicking machine comprising a frame, a cutting block mounted in the frame, a presser arm mounted for reciprocation heightwise of the block for producing pressure-applying operations upon the block, and power-operated means for reciprocating the presser member, said machine having means for initiating a single operation of the power-operating means including a solenoid, an electrically operated registering device in circuit with the solenoid, a starting switch in the circuit with the registering device and the solenoid, and a starting handle mounted upon the presser arm for effecting operation of the starting switch.

3. In a clicking machine having a cutting block, a presser arm mounted for movement heightwise of the block, power-operated means for effecting a reciprocation of the presser arm, electrically operated means for initiating operation of the power-operated means including in series a solenoid, a plurality of starting switches and a plurality of electrically operated registering devices, and a starting handle constructed and arranged to operate selectively the starting switches, thereby simultaneously to initiate an operation of the power-operated means and operation of one of the registering devices.

4. In a clicking machine having a frame, a cutting block carried by the frame, a presser arm mounted for movement toward and away from the block, and power-operated means for effecting reciprocation of the presser arm, a solenoid for initiating operation of the power-operated means, an electrical control circuit for the solenoid comprising a plurality of electrically operated registering devices, leads from one side of each of the registering devices extending in operative relation to one side of the solenoid, leads extending from the other side of each of the registering devices, respectively, to one side of each of a plurality of starting switches, leads extending, respectively, from the other side of each of the starting switches to the other side of the solenoid, and a manually operable member mounted upon the presser arm for selectively closing the starting switches.

5. In a clicking machine having a cutting block, a presser arm mounted for movement heightwise of the block and power-operated means for effecting reciprocations of the presser arm, the combination of a plurality of electrically operated registering devices, an electric circuit for initiat-

75

ing operation of the power-operated means comprising a solenoid, a plurality of starting switches, each of the registering devices having a lead extending to one side of the solenoid and each having a lead extending to one side of one of the starting switches, the other side of each of the starting switches being connected to the power line through the solenoid, and a starting handle for initiating operation selectively of one of the starting switches.

6. A clicking machine comprising a cutting block, a post mounted for reciprocation heightwise of the block, a presser arm carried by the post, and power-operated means for reciprocating the post, said machine having electrical means for initiating operation of the power-operated means including a solenoid, means for initiating an operation of the solenoid including in circuit a trip switch mounted at the top of the post and a starting switch mounted upon the presser arm, means for normally holding the trip switch in an operative position, means operable upon movement of the arm about the axis of the post for rendering the trip switch operative, and means for initiating an operation of the starting switch to effect a pressure-applying operation at such time as the trip switch is operated.

7. A clicking machine comprising a cutting block, a post mounted at one side of the block and arranged for reciprocation heightwise of the block, a presser arm carried by the post and movable over the cutting block about the axis of the post and heightwise with the post toward and away from the cutting block, power means for reciprocating the post, electrically operated

means for initiating an operation of the power means, a starting handle for controlling the initiating means, a trip switch located in circuit with the electrically operated means and comprising a contact carried at the upper end of the post and a movable contact, means normally operable to force the movable contact into engagement with the first-mentioned contact, means operable upon depression of the post to separate the contacts, and means operable upon subsequent elevation of the post to hold the contacts out of engagement with each other.

8. A clicking machine comprising a cutting block, a post mounted for reciprocation heightwise of the block, a presser arm carried by the post, power-operated means for initiating pressure-applying operation of the presser arm upon the block, an electrical circuit for controlling the operation of the power means including a solenoid, a starting switch and a trip switch, the trip switch comprising a fixed contact mounted at the upper end of the post and a lever arm pivotally mounted upon the frame of the machine and having a contact movable into engagement with the fixed contact, a spring normally operative to force the two contacts into engagement with each other, a latch carried by the lever, a pivoted plate arranged to engage the latch upon downward movement of the post and to separate the contacts upon a subsequent upward movement of the post, and means for disengaging the latch to permit engagement of the two contacts upon movement of the arm angularly a substantial distance about the axis of the post.

BASIL A. STROUT.
